UNITED STATES PATENT OFFICE.

JOHN HENRY BUCKLEY, OF FARNWORTH, NEAR BOLTON, ENGLAND.

SPINDLE AND BOBBIN OF RING-SPINNING AND RING-DOUBLING FRAMES AND THE LIKE.

1,326,179.

Specification of Letters Patent. Patented Dec. 30, 1919.

Application filed March 26, 1919. Serial No. 285,367.

To all whom it may concern:

Be it known that I, JOHN HENRY BUCKLEY, a subject of the King of Great Britain, residing at Farnworth, near Bolton, in the county of Lancaster, England, have invented certain new and useful Improvements in Relation to the Spindles and Bobbins of Ring-Spinning and Ring-Doubling Frames and the like, of which the following is a

specification.

The invention relates to the spindles and bobbins of ring spinning and ring doubling frames and the like, and has for object the provision of simple and effective means therewith whereby an increase in the speed of said spinning or twisting, and an increase in the amount or length of yarn spun and wound upon the cop or bobbin may be attained. Such means enable the cops of

yarn or thread to be formed on the bare spindle, or upon a smaller tube than the diameter of the ordinary bobbin, and with the use of the ordinary traveler and spinning ring.

It is well known that in ring spinning and ring doubling according to the means hitherto adopted, there is a variation in the tension or drag upon the yarn, which tension is greatest when spinning on the bare spindle or empty spool, and becomes less as the size of the cop increases. When the cop bottom is formed, the tension when spinning at the shoulder or large diameter of the chase is relieved by reason of the pull

of the yarn at the traveler being more nearly tangential to the ring than at other times. The conical shape of the cop however necessitates a movement of the ring rail as will result in succeeding layers of yarn being

wound on from the base of the cone or chase to the nose, or vice versa as is understood, so that as the nose of the cop is approached, the pull upon the yarn becomes less tangential to the ring, with a corresponding gradual increase in the tension or drag upon said yarn, until the nose is reached, after which the tension gradually decreases as spinning and winding proceed toward the larger diameter again.

In order to minimize this difficulty of increased tension as described, a common practice is to use fairly large diameters for the

bobbins or spools compared with the particular size or diameter of the ring employed. The objection to this is the reduced holding capacity of the bobbin, necessitating more frequent doffing, as well as incurring higher cost in the subsequent process of winding or reeling, also there is introduced more winders' or reelers' knots in the yarn.

In carrying out my invention, and whether applied to spindles used for spinning "weft way" or for "twist" spinning, I provide a member, such as a disk of metal or other suitable substance, which is capable of being passed about or on to a spindle or bobbin or tube, and of being moved up the same, by the action of the yarn, as the building of the cop or bobbin proceeds.

The yarn travels over or about the edge or periphery of said member before it passes to the ordinary traveler on the spinning ring. By this means, the diametrical distance from the axis of the spindle to the point at which the yarn touches the member or so passes over the edge (when the yarn is not ballooning) is a constant or approximately so, at all heights during the building up process under the conditions referred to. The effect of this is that, the yarn and, with it, the traveler are carried around, increased tension of the yarn which would occur in ordinary circumstances, being obviated.

Increased speed of spinning, with fewer broken ends thus becomes possible. Added to which, the employment of the member referred to, enables spinning to be accomplished upon a thinner bobbin or pirl than usual, or even upon the bare spindle itself, giving increased amount or length of spun material wound upon the same.

With reference to the accompanying drawings, Figure 1 shows a member or device according to one form of my invention, and Fig. 2 shows a cop spindle and adjacent parts, in sectional elevation, with the said member in position thereon. Fig. 3 shows some portion of Fig. 2, with a part of a cop formed thereon, and Fig. 4 is a similar view with the cop about built up completely.

Fig. 5 is a modified member or device, and Fig. 6 is a form of spindle suitable therefor.

Fig. 7 shows a bobbin spindle provided with a paper or other bobbin of comparatively small diameter.

Fig. 8 shows a member or device in position for being doffed off the spindle by a clip arrangement indicated.

With reference to Figs. 1 to 4 inclusive, *a* is the cop spindle provided with the usual wherbe *b* for being driven from the tin roller 10 on the frame. *c* is the ring, and *d* the traveler mounted thereon. *e* is the ring rail movable in a vertical direction, by the usual poker methods, for enabling the cop to be properly built up.

h is the yarn to be spun and wound upon the spindle *a* to form the cop. *i* is a member with a rough edge or according to one form provided with ratchet like teeth, regularly or irregularly spaced apart at its periphery, 20 and having a hole *j* therein to enable the device or member to be passed on to and down the spindle *a*. The member *i* is shown provided with a preferably dished portion *i*¹, in this instance, for the purpose to be named 25 hereafter. At the commencement of spinning operations on a bare spindle, I prefer to make use of a paper tube, of any suitable form and diameter, such as at *k*, for supporting the member *i* until such time it can 30 be supported by the wound on yarn. I prefer that the diameter of the member *i* be a mean between the inner and outer diameters of the ring *c*, but other dimensions of the member *i*, whether greater or less than indicated, may be employed.

In Fig. 3 the cop is shown partly built up by succeeding layers of wound on yarn, according to the operation of the ring rail *e* of Fig. 1, which cop portion at its upper end 40 supports, turns and lifts the member *i* as said cop portion develops. But frictional contact with spindle *a* may help to turn member *i*.

At the position shown in said Fig. 3, the 45 tension of the yarn *h* is assumed to be sufficiently relieved to allow of a slight ballooning of the yarn away from the spindle *a* and the member *i*. To enable this to be possible, the yarn *h* must be quite free from any restraining influence between the traveler *d* and the usual guide or curl (not shown) above the spindle point. In this sense the yarn may be referred to as being unrestrained. 50 At such time, the office of member *i* is not required to be performed, but as the yarn forming the portion of the cop shown is nearer to the spindle *a* at the upper part of said cop portion, the tension during winding at that part might be sufficient to reduce 55 the ballooning so that the yarn *h* bore against the edge of the rotating member *i*. A similar condition is shown in Fig. 4, where the tension near the nose portion of the cop being formed is considerable, comparatively 60 speaking. It will be seen that while ever in

contact with the member *i*, the yarn *h* is kept thereby at a constant distance from the spindle *a* and is being carried around by said member, thus preventing the yarn from the usual thread guide taking a direction or angle such as indicated by broken line in Fig. 4 aforesaid.

When using toothed projections for the member *i* as in Fig. 1 for carrying around or rotating the yarn, I may arrange the member *i* in position on the spindle so that it turns in the negative direction as regards said teeth. This is to facilitate the sliding off of the yarn from the teeth when ballooning occurs.

Means may be provided for keeping the edge portions of the member *i* clear of the ring or traveler as the same approaches the member during spinning and winding. Said means here illustrated consist of the dished 80 part *i*¹.

By reversing the member, so that its upper side shown is made the underside, it becomes suitable for being turned in the opposite direction. In such case it could 90 be provided with a projecting part or parts on that reverse side for fulfilling the office of dished part *i*¹. Or it could be flat if desired.

Means may be provided for enabling the 95 member *i* to be driven positively by the spindle *a*, as an example in Fig. 5 member *i*, with a central aperture *j*, and projecting parts *i*² is shown, the latter being capable of engaging grooves in or being in gear 100 with a spindle *a*, one of said grooves being indicated at *a*¹ in Fig. 6. These grooves would be deeper toward the lower end of the spindle, so that on the member *i* being mounted on the spindle *a*, the projections *i*² 105 would always prevent the upper part of the nose of the cop passing into the aperture *j* of the member *i* and so reaching a level above said member. Added to which, the projections *i*² would thus insure the 110 member *i* always riding on the top of the nose of the cop, a taper spindle being assumed as shown.

In said Fig. 5 the edge of the member *i* is shown differently provided to the case 115 of Fig. 1, or the edge is capable of being engaged by the yarn but will allow said yarn to slip away when and as described.

In Fig. 7, *l* is an ordinary form of bobbin spindle, which I may supply with a paper 120 or other bobbin *m*, having by preference parallel sides down to the swelled portion, and of comparatively small diameter at said parallel part. The member *i* therefor, would have a central aperture to suit. The 125 bobbin could be grooved as in the case of the spindle *a* in Fig. 6 if desired, and the member *i* constructed to engage same.

In Fig. 8, a member of similar form to the one shown in Fig. 1, is assumed to be one 130

of many mounted on respective spindles *a*, and at the period when the cops are completed and doffing of the members *i* desired. A board *n*, provided with gaps such as *o* (one for each spindle operated upon) is capable of being pushed toward the spindles *a* or toward the bobbins, so that each gap *o* may engage a part of each member *i*, for example, a projecting boss *i** below and about the aperture *j*, and indicated in broken lines in the figure.

By the sliding of the board under a number of members forming a section of the total, the same may be doffed or lifted off the spindles at one operation. And for retaining them in position on the board *n*, ready to be dropped on to the spindles again, spring devices such as spring clips *p* on the under side of said board *n* may be provided.

In the case of Fig. 5 and Fig. 6 the member *i* would be positively carried around by the spindle *a*, but in other cases where no direct connection between the spindle and the member exists, the latter would be carried around by frictional contact with the top of the nose of the cop or the like on which it rested or was supported thereby,

or by whatever support was provided for it in this manner.

In some cases the members *i* may be doffed singly. The spindle, bobbin, or tube upon which the spun yarn is wound, may be termed a "yarn container".

I claim:—

1. In ring spinning and ring doubling frames and the like, in which the yarn is unrestrained, a horizontally situated yarn-rotating member passing about a yarn container, and riding upon the top part of the wound on yarn, said member provided with a serrated vertical edge, for the purpose and in manner substantially as herein set forth.

2. In ring spinning and ring doubling frames and the like, a horizontally situated yarn-rotating member in the form of a disk, passing about a yarn container, said member in frictional contact with the top part of the wound on yarn, and said member provided with a serrated vertical edge in the form of ratchet-like teeth, for the purpose and in manner substantially as herein set forth.

In testimony whereof I have affixed my signature.

JOHN HENRY BUCKLEY.
